VACUUM CLEANER

Henry T. Lang, Cleveland, Ralph E. Dunbar, East Cleveland, and Joseph Hrach, Cleveland, Ohio, assignors to Electric Vacuum Cleaner Company, Inc., Cleveland, Ohio, a corporation of New York

Application June 24, 1941, Serial No. 399,474

3 Claims. (Cl. 15—16)

The present invention relates to portable vacuum cleaners of the type having a horizontally arranged motor.

The object of our invention is to provide an improved construction and arrangement in vacuum cleaners of this type, and for a consideration of what we believe novel and our invention, attention is directed to the following description and the claims appended thereto.

In the drawing, Fig. 1 is a sectional elevation of a vacuum cleaner embodying our invention; Fig. 2 is an exploded view of the base element of the vacuum cleaner; and Fig. 3 is a perspective view of the resilient support for the front end of the motor.

Referring to the drawing, there is shown a vacuum cleaner in which the parts are arranged on a base element comprising upper and lower castings 1 and 2. The lower casting 2, which comprises the main part of the base element, has a skirt 3 on which is pivoted a handle fork 4 and has a horizontal web 5 within the skirt on the under side of which are mounted front and rear supporting wheels 6 and 7. On the upper side of the web are vertical walls 8 and 9 having seats 10 and 11 providing a cradle for an electric motor 12. The motor is resiliently supported in the seat 10 by a rubber ring 13 surrounding a boss 14 at the rear of the motor and clamped to the seat by a strap 15. The motor is resiliently supported in the seat 11 by a rubber ring 16 having an irregular opening 17 snugly receiving a boss 18 at the front of the motor and having ribs 19 defining a groove receiving the edges of the seat 11. The ring 16 is clamped in the seat 11 by the upper casting 1. While the rubber ring 13 serves solely as a resilient support for the motor, the rubber ring 16 in addition serves as an air tight seal between the motor and the wall 9 which is the rear wall of the fan casing. The motor has a shaft 20 extending through an inlet opening 21 in the front wall 21a of the fan casing into a suction chamber which terminates in a suction nozzle 22 having a rotary agitating element 23 driven by a belt 24 from the extended end of the motor shaft. Opposite the end of the shaft extension is a suction opening 25 in the front wall of the suction chamber which is normally closed by a suction plate 26. Upon removal of the suction plate 26 and the belt 24, a suction hose may be connected to the fan inlet through a converter tool inserted through the suction opening 25 into sealing engagement with the fan inlet 21 in a manner well understood in the art. Dust-laden air is drawn 55

into the fan inlet 21 by a fan 27 fixed to the motor shaft and is discharged through an outlet conduit 28 integral with the casting 2 which may be connected to the conventional bag. The top casting 1 of the base element comprises a hollow section 29 which serves as the top of the fan casing and a tongue 30 which fits in and closes a slot 31 in a wall 32 on the casting 2 which serves as the top wall of the suction chamber. 10 Upon removal of the top casting the motor and fan may be lifted out as a unit from the lower casting 2. The slot 31 serves as a passageway for the motor shaft extension.

The upper and lower base castings 1 and 2 and the parts heretofore described constitute a complete operative vacuum cleaner. The manufacture and assembly is simplified by the fact that all of the operative parts are mounted on the lower casting.

15 The upper side of the vacuum cleaner is enclosed by a hood 33 secured to the lower casting 2 by screws extending up into the hood through bosses 34. At the rear, the hood rests on and blends smoothly into the contour of the skirt 3. At the front, the hood rests on the upper edge of a wall 35 which constitutes a continuation of the skirt. The skirt 3 and the wall 35, in addition to providing a smooth exterior surface enclosing the operating parts of the cleaner, serve as reenforcing walls for the lower casting 2 of the base element. As shown in Fig. 1, the hood is spaced above the wall 32 which serves as a shelf supporting an electric light 36 indicated in dotted lines in Fig. 1. A projecting lip 37 on the hood provides a slot through which the light shines to illuminate the surface in front of the nozzle.

20 It will be noted that the hood does not support any of the operating parts of the cleaner and that it is protected from impact by the skirt 3, by the wall 35 and by the nozzle. The hood accordingly can be made of a material having low strength and resistance to shock such as a molded plastic.

25 45 What we claim as new and desire to secure by Letters Patent of the United States is:

1. A vacuum cleaner having a base element comprising a suction chamber, a fan chamber, and a cradle for a horizontal motor in the order named from front to rear, a motor on said cradle having a fan on its shaft and having a shaft extension in the suction chamber for operating an agitating element, the top wall of the suction chamber providing a shelf for an electric light below the top of the fan chamber, and a

hood on the base element covering said shelf and the motor and the fan chamber, said hood providing a light-transmitting passageway directed toward the surface in front of the suction chamber.

2. A vacuum cleaner having a base element comprising a suction chamber, a fan chamber, and a cradle for a horizontal motor in the order named from front to rear, a motor on said cradle having a fan on its shaft and having a shaft extension in the suction chamber for operating an agitating element, said cradle including a skirt on said base element depending around the motor and a web extending across the skirt beneath the motor, said skirt having vertical walls of U-shaped contour with the base of the U at the rear of the motor and the arms of the U on opposite sides of the motor with the ends thereof blending into the fan casing, means within the skirt for fastening the motor to the cradle, and a unitary hood enclosing said fastening means and the top of the motor and of the fan suction chambers, the lower edge of said hood being adjacent the upper edge of said skirt and

the side walls of the hood forming a continuation of the skirt.

3. A vacuum cleaner having a base element comprising a suction chamber having top and side walls of a suction nozzle at its lower end, a fan chamber, and a cradle for a horizontal motor in the order named from front to rear, said base element comprising complementary upper and lower parts, the upper part comprising the top of the fan chamber, and the lower part comprising the suction chamber, the lower part of the fan chamber and the cradle and vertical walls on said lower part forming a skirt depending around the sides and rear of the cradle and merging into the front walls of the suction chamber and the top walls of the suction nozzle on opposite sides of the fan chamber and forming a continuation of the skirt and a hood for the motor and the fan and suction chambers, the lower edge of the hood being adjacent the upper edge of said vertical walls.
